DESIGN FOR A FLASH LAMP OR SIMILAR ARTICLE

Samuel Osterman, New York, N. Y., assignor to Guth, Stern & Co. Inc., a corporation of New York

Application May 17, 1935, Serial No. 56,883

Term of patent 7 years

To all whom it may concern:

Be it known that Samuel Osterman, a citizen of the United States and resident of New York city, in the county of Kings and State of New York, has invented a new, original, and ornamental Design for a Flash Lamp or Similar Article, of which the following is a specification, reference being had to the accompanying drawing, forming part thereof, in which, the figure is a perspective view showing my new design.

I claim:

The ornamental design for a flash lamp or similar article, as shown.

SAMUEL OSTERMAN,
